[57] CLAIM

The ornamental design for a speech synthesizer activated by reading of a magnetic card, as shown and described.

DESCRIPTION

FIG. 1 is a top, front perspective view of a speech synthesizer activated by reading of a magnetic card showing my new design, with the cover of the reading slot being in the open, operational position;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof;

FIG. 8 is a top, front perspective view thereof, with the cover of the reading slot in the closed position; and

FIG. 9 is a rear elevational view thereof, with the cover in the closed position.

FIG. 1

FIG. 2

FIG. 3

FIG. 4

FIG. 5

FIG. 6

FIG. 7

FIG. 8

FIG. 9
